UNITED STATES PATENT OFFICE.

JOHN FELKEY, OF BEMIDJI, MINNESOTA.

CAR-STAKE.

No. 880,982.

Specification of Letters Patent.

Patented March 3, 1908.

Application filed November 1, 1907. Serial No. 400,147.

To all whom it may concern:

Be it known that I, JOHN FELKEY, a citizen of the United States, and a resident of Bemidji, in the county of Beltrami and State 5 of Minnesota, have invented a new and Improved Car-Stake, of which the following is a full, clear, and exact description.

This invention relates to stakes that are used for the lateral support of timber or logs, 10 piled as a load upon a platform-car, and has for its object to provide novel details of construction for a car-stake, which will reliably hold it erected and permit the ready release of the stake, so that it may be rocked into a 15 plane below the bottom of the car for a convenient lateral removal of the load therefrom.

The invention consists in the novel construction and combination of parts, as is 20 hereinafter described and defined in the appended claims.

Reference is to be had to the accompanying drawings forming a part of this specification, in which similar characters of reference 25 indicate corresponding parts in all the figures.

Figure 1 is a side view of a portion of a platform-car and of two stakes having the improved feature, one stake being held erect and the other stake lowered into a pendent 30 position; Fig. 2 is an enlarged transverse sectional view of the platform of a car, and a side view of the improved car-stake thereon in erected condition, the section being substantially on the line 2—2 in Fig. 1; Fig. 3 is 35 a sectional plan view of the improved stake, substantially on the line 3—3 in Fig. 2, and Fig. 4 is a detached perspective view of a lever that embodies novel details and is a feature of the improvement.

40 In the drawings, that show the invention and its application, A represents a platform-car of ordinary construction, having the usual side timber A' thereon, which may be a portion of the car-frame. The body 5 of the 45 car-stake is of metal, T-shaped in cross section and preferably cast into shape, the lower end of said body being hinged at a upon a bracket-plate 6, that is secured upon the side timber A'. An ear a', which projects outward from the bracket-plate, permits the pivotal attachment of the lower portion of the stake body 5 at such a distance from the car-timber A' as will enable 50 the erection of the stake in an upright position close to said timber.

Upon the side of the body 5 that is outer-

most when the stake is erected, and at a suitable distance above the hinged lower end thereof, two spaced boxes b, b, are secured, between and in which a lever 7 is pivoted by 50 means that will be described. The lever 7, as shown clearly in Fig. 4, is substantially in the form of an inverted T, the body thereof having, at the lower end integral transverse members 7^a, that are extended at right 55 angles to said body 7 equally on each side thereof, and providing journals which are fitted loosely in the boxes b, b, that permit the free rocking movement of the lever thereon.

Two chain cables 8 are employed as means for holding the body 5 of the stake erected, and as appears for one chain, they are extended from the car body or transverse timber thereof outwardly of an equal length, 75 which permits the outer ends of the cables whereon are oval links or rings c, to be passed over the projected ends of the members 7^a.

To facilitate the attachment and removal of the ends of the cables, the respective ends 80 of the members 7^a that are extended outside of the boxes b, are rendered conical and bent forwardly, thus giving them the form of horns d.

It will be seen that the relative positions of 85 the horns d on the lever 7, will cause said horns to project forward when the lever is rocked into an erect position, but when it is rocked in a reverse direction a sufficient distance so as to dispose it pendent, the points 90 of the horns d will be turned inward or toward the body of the stake 5.

In service, the stakes of improved construction, that are arranged at intervals along the sides of a platform car, are permitted to hang pendent, as shown for one stake in Fig. 1, which will permit the car to be loaded with material, that may be lumber, timber or logs. After the car is loaded, the stakes are rocked into vertical positions, but 100 the levers 7 hang down at the sides of the stakes. The pendent positions had by the levers dispose the horns d for reception of the rings c, which may be freely placed thereon and located close to the boxes b, b.

The lever 7 on each stake 5, is now rocked upward, which will turn the horns d outward and thus adapt them for retaining the rings c on the members 7^a of the levers. For retention of the levers in upright positions, a 110 keeper arm 9 is provided for each arm, consisting of an L-shaped metal bar journaled

at the end of one limb thereof in a perforation in a respective stake, and so positioned that the other limb will be adapted for locking engagement with the lever, when it is vertically disposed and said limb is rocked across the lever, as shown in the drawings.

Upon the normally upper end of each stake 5, a ring *e* is loosely secured, these rings affording means for securing an upward 10 tension on the stakes 5 if this is desired.

The upper end of each lever 7 is preferably perforated and receives a ring *g*, that in turn is connected with the end of a small rope or chain *h*, the latter having such a length as 15 will permit its manipulation when necessary.

Obviously, for conveniently unloading a car at each or either side thereof as is customary, the stakes 5 must be released and allowed to hang down out of the way. To effect such 20 an adjustment, the keeper arms 9 are turned around so that their locking limbs will be removed from the levers 7.

The flexible connection *h* for each lever 7, is now pulled upon, which will rock the lever 25 downward and so dispose the hooks *d*, as before explained, that the rings *c* may be readily detached therefrom, whereupon the stakes thus released may be rocked downward, as indicated by dotted lines in Fig. 2.

Having thus described my invention, I 30 claim as new and desire to secure by Letters Patent:

1. A car stake, comprising an elongated metal body, a bracket plate hinged upon the 35 normally lower end of said body, chains extended from the car, and a lever pivoted on the stake and having lateral projections that

receive the ends of the chains when the lever is pendent, and retain the chains engaged therewith when the lever is rocked upwardly. 40

2. A car stake, comprising an elongated metal body, a bracket plate hinged on the normally lower end of said body, chains extended from the car, and a lever having lateral extensions that are journaled in boxes 45 or the like on the lever, said extensions having conical bent ends forming horns and the chains terminating in rings that will engage with the horns or may be removed therefrom when the lever is pendent, said rings being 50 held in place on the horns when the lever is erected.

3. A car stake, comprising an elongated metal body, a bracket plate whereon the lower end of the body is hinged, chains having rings on their outer ends and extended from the car body, a lever having integral extensions that terminate in horns bent in the same direction, boxes on the stake that receives journaled portions of said extensions, 60 the rings on the chains engaging the horns when the lever is pendent and being retained thereon when the lever is rocked upward, and a keeper arm adapted for adjustment and contact with the outer side of the lever for 65 its retention in an upright position.

In testimony whereof I have signed my name to this specification in the presence of two subscribing witnesses.

JOHN FELKEY.
